UNITED STATES PATENT OFFICE.

LUTHER W. SPRINGSTEIN, OF BINGHAMTON, NEW YORK, ASSIGNOR OF ONE-HALF TO
ADELBERT E. BENEDICT, OF BINGHAMTON, NEW YORK.

MAIL-CATCHER.

1,130,035.

Specification of Letters Patent.

Patented Mar. 2, 1915.

Application filed November 1, 1913. Serial No. 798,723.

To all whom it may concern:

Be it known that I, LUTHER W. SPRINGSTEIN, a citizen of the United States, residing at Binghamton, in the county of Broome 5 and State of New York, have invented new and useful Improvements in Mail-Catchers, of which the following is a specification.

This invention relates to mail bag receiving mechanism and it has for its primary 10 object the provision of mechanism for receiving the bag in a manner which will positively prevent damage to the contents of the bag while in action.

Another object of the invention is the 15 provision of mechanism of this character in which the receiving arm will be provided with means to prevent the accidental derangement therefrom of the bag instantly on receipt of the latter and which will consist of a member which will be actuated 20 through its direct contact with the bag.

A further object of the invention is the 25 provision of mechanism of this character which will serve to completely house or inclose the bag immediately on its receipt so as to prevent the bag being tampered with by any one excepting an authorized agent.

A still further object of the invention is the 30 provision of an inclosure having an opening therein at one side and a swinging receiving arm mounted within the inclosure and adapted to be adjusted to a receiving position beyond the opening, and further the provision of mechanism which will be 35 actuated directly through movement of the receiving arm for respectively holding the closure in opened and closed positions.

With these and other objects in view, the 40 invention consists of certain novel features of construction, combination and arrangement of parts, as will be hereinafter described and claimed.

In the accompanying drawings:—Figure 1 is a horizontal section through a portion 45 of a car, showing the application of the invention thereto and illustrating the receiving arm in a receiving position; Fig. 2 is a section on line 2—2 of Fig. 1; Fig. 3 is a section on the line 3—3 of Fig. 1; Fig. 4 is 50 a horizontal section through the receiving mechanism by means of which the bag may be received from a moving car; Fig. 5 is a vertical section therethrough; Fig. 6 is a

vertical section through a portion of the roller, showing the return spring for moving 55 the door to a closed position.

With a view to providing bag receiving mechanism which will be operable to receive the bag in a manner which will prevent or minimize the possibility of its contents being injured during the receiving operation; one wherein the bag will be held 60 positively against accidental derangement from the receiving means after collected thereby; and, further, means which will automatically operate to effect a total or absolute inclosure of the bag after it has been taken up or collected by the receiving means, I employ an inclosure A as shown in Fig. 1, 65 which may be in the nature of a carrier such as an ordinary railway car or other form of traveling coach, or a form of inclosure B such as shown in Figs. 4 and 5 and which is designed to form a substitute for or to replace the well known form of stationary 70 mail cranes commonly employed for the purpose of receiving the bag from a moving vehicle or car.

As the invention, when broadly construed 75 is designed for the above specified purposes, it may be specifically described, when reference is taken to Figs. 1, 2, 3 and 6 of the drawing that the inclosure A representing an ordinary railway car is provided at one side with the usual door opening C. Rising 80 from the floor of the car are standards 1, 1 of identical construction, arranged with such regard to the opening C whereby to permit the standard to be interchangeably 85 connected with bag receiving means and to support the latter in a position that may be 90 necessary to a collection of the bag, according to the direction of movement of the car. As the standards 1 are of identical formation it is thought that a description of one 95 will suffice for both and with detailed reference to Fig. 1 it is seen that the standard to the right is provided with a slot 2 in which is fitted the reduced stem 3 upon the arm 4 of bag receiving means 5. The standard has 100 its opposite ends respectively mounted in portions 5 and 6 of the car structure whereby the standard is free for rotation. This is desirable, and in fact necessary in order that the receiving means as a whole may be 105 projected into the inclosure or car A when

it is desired to effect a total housing or concealment of the bag after the latter is received.

The arm 4 is disposed in a horizontal position and its attaching end 3 is secured to the standard 1 by means of a suitable retaining pin 7 or the equivalent thereof which is adapted to be passed through a passage 8 in the standard which is intercepted by the passage 2. At one end the shank of the member 7 is provided with a removable cotter pin or the like 9, whereby said member is held in an applied position. At the outer receiving or collecting end the arm 15 is bifurcated or forked and provided with companion branches 10 and 11 of varying lengths. These branches are connected with each other by a bight or curved connecting portion 12. The branch 11 is curved outwardly from the bight 12 and disposed at such an angle to the branch 10 as to define therewith an intervening bag receiving space of a restricted size in the direction of the bight 12. A retainer of substantially V-form is pivoted at 13 to the arm 4 at a point contiguous of the branch 10 and as shown said retainer is provided with a curved branch or arm 14, which is adapted to be initially extended over the open end 30 of the fork, as shown in Fig. 1, where it will be directly located in the path of the bag, as will be appreciated. The other arm 15 of the retainer is located with such relation to the arm or branch 14 that when the latter spans or extends over the receiving end of the fork the terminal of the arm 15 will define with the terminal 16 of the branch 11 of the fork, a substantially flared passage so as not to interfere with the bag on its movement into the fork. When the bag contacts with the branch 14 of the container it obviously appears that the retainer will assume the dotted position shown in Fig. 1, so that the branch 15 of the retainer will close the open end of the fork and confine the bag against the bight of the fork and in such manner that will positively prevent accidental derangement of the bag.

It is desirable to hold the retainer in a closed position after it has been actuated by the bag as previously mentioned and in view thereof I provide a locking device therefor which consists preferably of a flat spring 17 secured to the arm 4 and provided at its free end with a fixed pin 18. This pin moves in a passage 19 in the arm and when the retainer is adjusted to the dotted line position shown in Fig. 1 the said pin is designed to repose automatically in a recess 20 formed in the retainer at the vertex between the branches 14 and 15. The fork of the arm 4 is provided with a stop pin or lug 21, against which the free terminal of the branch 14 is adapted to engage as shown in full lines in Fig. 1. It is described that the

pin 18 bears yieldingly against the upper surface of the retainer at the vertex of the arms 14 and 15 and under the action of the spring 17, the retainer will be positively held in the active full line position shown in Fig. 1. In other words there is sufficient friction between the parts mentioned to prevent the retainer casually moving to a position other than that intended prior to receiving the bag. Ordinarily or without providing the means above referred to for the purpose specified, the vibrations of the car might tend to cause the retainer to shift from its intended position, as will be understood.

The arm 4 is adapted through its impact with the bag to be moved completely into the car and as illustrated the car is provided with a horizontally sliding door or closure 22 which is adapted to be automatically moved to a position to close the opening C on the instant that the arm 4 is moved into the car and entirely through the opening C. In order to effect this automatic closing of the door I provide the car with a roller 23 having one end of a flexible connection 24 connected therewith, while the opposite end of the connection is secured at 25 to the door. The roller is provided with a spring tensioned or controlled pintle 26 by means of which the roller will tend normally to revolve in one direction and to thereby cause the connection 24 to be wound on the roller and with a resultant adjustment of the door to a closed position over the opening C.

It is necessary that the standard 1 be held against rotation when the arm 4 is in a bag receiving position and with this necessity in view I make use of a flat spring 27 having one end connected to a suitable permanent device 28 and having its opposite end extending across the adjacent flat side of the standard. At this time it may be mentioned that the standard is of rectangular form in transverse section so as to provide flat sides against which the spring 27 is adapted to bear. The free end of the spring extends slightly beyond the adjacent side of the standard so that one corner of the standard will be advanced against the spring and on movement of the standard respectively to active and inactive positions the spring will be moved laterally or with relation to the adjacent side of the car. This last-named arrangement is desired for the reason that I have employed locking means for holding the door 22 respectively in opened and closed positions. The locking means now referred to is in the form of a sliding bolt 29 which is adapted to engage in a keeper recess or notch 30 formed in the door and to thereby hold the door in the opened position shown in Fig. 1. The bolt is positioned with such regard to the

adjacent side of the door opening C, that when the door is closed the bolt will engage against the adjacent edge of the door and thereby hold the same against being opened 5 from the out side. From the inside the bolt may be released by simply swinging the arm 4 manually so as to cause sufficient movement to be imparted to the spring 27 that is necessary to retract the bolt.

10 Now that the details of the described embodiment of the invention are specifically mentioned it is stated that under the impact of the bag against the arm 4 the latter will be instantly moved into the car or inclosure 15 and immediately thereupon the bolt 29 will be controlled and under the action of the spring roller 23 the connection 24 will be wound upon the roller and door 22 moved to its closed position. The bag is then held in 20 a completely inclosed or housed state and cannot be tampered with fraudulently by persons from the outside.

While the receiving mechanism may be advantageously used in connection with mail 25 coaches or like traveling vehicles I desire that it be understood that I also contemplate using the same as a substitute for the well known form of crane, therefore, and with detailed reference to Figs. 4 and 5 of 30 the drawing I provide an inclosure B hereinbefore mentioned and at one side I form therein an opening 31 over which is adapted to move a vertically sliding door 32. The standard 1^a which supports the receiving 35 arm 4^a is identical with that previously referred to. A roller 23^a which is substantially identical with the roller 23 is also employed and provided with a connection 33 secured at 34 to the door at the bottom thereof. 40 The door is provided with a keeper opening 35 which is adapted to receive a swinging spring-pressed locking dog or bolt 36 so that the door will be held normally against the spring action of the roller 23^a. The dog 36 45 has connected therewith one end of a link 37, the opposite end of the link having connection with one end of a rocking lever 38. The free end of the lever extends across one of the flat faces of the standard 1^a and 50 slightly beyond the adjacent side of the standard, as shown in Fig. 4, thus it will be seen that when the standard is rotated under the swinging action of the receiving arm 4^a

to an inactive position the said lever 38 will be rocked and the link 37 drawn upon in such manner that will necessitate an operative release of the dog 36 from the keeper opening 35 in the sliding door. In this form of sliding door I provide the inclosure, at a point above the door opening with a 55 swinging keeper or bolt 39 which is adapted to engage in a keeper recess 40 formed in the door near the upper end thereof. This dog or bolt is connected by a cable 41 and the latter may be run over a guide pulley 42 60 and then extended to a point in the inclosure where it may be readily grasped by the hand and pull applied thereto so as to tilt the bolt or dog 39 and render the same inactive in order that the door 32 may be 65 opened. At the opposite sides the inclosure is provided with a swinging door 43 of any suitable well known form by means of which a lawful agent may enter the inclosure in order to receive the bag collected or to adjust the mechanism as the occasion may demand. It is obviously understood that the closure 43 may be held in a closed position by a suitable form of lock 44. The inclosure B is preferably constructed of metal 80 or other fire-proof and burglar proof material and it is also designed whereby to protect the bag and its contents from the elements.

75 I claim:—

85 A mail bag receiving apparatus comprising an inclosure having an opening, a movable closure for the opening, a rotary standard arranged within the inclosure and having flat faces, a mail bag catcher arm carried 90 by the standard and adapted to be projected through the opening, means for tensioning the closure for automatically moving the same for closing the opening, a lock 95 for holding the closure open or closed, a trip member displaced by the flat faces on the standard when rotated and having connection with the lock for operating the same and also for holding the standard in adjusted position.

100 In testimony whereof I affix my signature in presence of two witnesses.
